United States Patent Office.

E. B. SINTZENICH, OF ROCHESTER, NEW YORK.

Letters Patent No. 91,173, dated June 8, 1869.

IMPROVEMENT IN STEAM-GENERATORS.

The Schedule referred to in these Letters Patent and making part of the same.

To all whom it may concern:

Be it known that I, E. B. SINTZENICH, of Rochester, county of Monroe, State of New York, have invented certain new and useful Improvements in Steam-Boilers; and I do hereby declare that the following is a full, clear, and exact description thereof, reference being had to the accompanying drawing, making part of this specification, in which—

Figure 1 is a vertical central section, showing one-quarter of an ordinary upright boiler, and the water-tubes *a b c d* in elevation.

Figure 2 is an outlined top view, showing the arrangement of the steam-chamber *C*, reduced.

The objects of my invention are, mainly, to utilize more perfectly the core of heat rising in the vertical flues, and also to produce a constant circulation of water in the boiler; and

Its nature, which will be better understood by reference to the drawings and specification, consists, principally, in locating a vertical water-tube in the centre of each fire-flue, the tubes being connected at top and bottom with the shell of the boiler.

To enable others to make and use my invention, I will describe its construction and operation.

In the furnace *B*, fig. 1, of the upright boiler *A*, I provide the chamber *C*, joining the annular water-space at opposite sides, and dividing the furnace into two parts.

In the smoke-box *D*, I also provide a corresponding steam-chamber, *C*, figs. 1 and 2, connected in a similar manner. These chambers subserve several purposes.

The steam-chamber *C* increases the steam-room, and at the same time presents additional surface to the action of the heat.

The water-chamber *C* also increases the heating surface, and divides the furnace into two independent furnaces, and the flat sides of both chambers provide a ready means of connecting the water-tubes *a b c d*.

The water-tubes *a b c d*, fig. 1, I arrange centrally in the fire-tubes or flues *a' b' c' d'*, the annular spaces between them being large enough to allow sufficient draught.

These tubes *a b c d* are screwed, at their lower ends, into the double elbows *x x*, which are made long enough to reach from centre to centre of the flues, and, at their lower sides, are provided with branches *t t*. Into the branches *t t* are screwed the short pipes *o o*, which are secured to the sheet of the boiler by an arrangement described below.

The upper ends of the tubes *b* and *c* are screwed into the elbows *f* and *f'*.

These elbows I connect by means of the hollow union nut *e*, shown in section in fig. 1, provided with a left-hand thread at one end, and a right-hand thread at the other.

From the elbow *f*, I extend the branch-pipe *o*. Since the pipes *o o* and *o' o'* are secured to the sheet in an exactly similar manner, I will describe but one of them.

The pipe *o* is threaded at both ends, and the nut *g* applied at the end which is screwed through the sheet *i*.

The sheet being tapped out, the pipe *o* is screwed into it far enough to allow the opposite end to enter the elbow *f*, when, by turning it backward, the joint in the elbow is made tight. The pipe *o* still remaining screwed into the sheet.

The nut *g* is now screwed up against the latter, making a perfect joint.

The pipes *a* and *d* are screwed into the elbows *j* and *k*, which, in turn, are connected with the boiler, as described above.

The object of the union nut *e* and pipes *o o o' o'*, arranged as described, is to provide a ready means of putting the pipes *a b c d* together, when in their positions.

The outside shell of the boiler I offset outward, as shown at *m*, fig. 1, for the purpose of obtaining additional steam-room.

My invention can be made of ordinary gas-pipe and fittings, and inserted by a skilled mechanic, in any boiler having vertical flues, without altering its arrangement.

The circulation of the water is shown by the arrows, and takes place not only from bottom to top, but also from the centre to outside, as shown.

I prefer to arrange the water-tubes in sets of four, which may be repeated throughout the boiler, but they may be used singly, or in sets of two or three.

My invention is particularly applicable to steam fire-engine boilers, as by means of the water-tubes I expose a large additional fire-surface, with a small proportional quantity of water.

I have found, by experiment, that I can raise steam in an ordinary fire-engine boiler, with my invention attached, in from six to eight minutes.

It is also well adapted to marine purposes, for vertical boilers having two or more furnaces, and for all square or irregular-shaped boilers having vertical flues.

The chambers *C* and *C'* may or may not be used, according to circumstances; or two of each may be used, cutting each other at right angles.

In case none are used, the connections of the pipes *a b c d* would be all made to the inside shell of the boiler.

The operation of my invention is as follows:

The water-tubes *a b c d* being arranged in the centre of the fire-flues, the hottest flame impinges on them, since the centre of any cylindrical flame is the point of greatest heat.

By this means steam is raised very fast in the tubes, and the bubbles of vapor rising in them, puts the columns of water in motion in the manner shown.

What I claim as my invention, and desire to secure by Letters Patent, is—

1. The combination and arrangement of the water-tubes *a b c d* with reference to each other, and to the steam and water-spaces of upright boilers, substantially as described.

2. The steam-chamber *C*, with its corresponding water-chamber *C'*, communicating with the annular

steam and water-spaces of upright boilers at opposite sides, in combination with the water-tubes *a b c d*, substantially as set forth.

E. B. SINTZENICH.
